SCREEN DOOR GRILLE

Louis A. Macklanburg, Oklahoma City, Okla.

Application August 25, 1949, Serial No. 112,322

4 Claims. (Cl. 160—89)

1

The present invention relates to push grilles for protecting the wire mesh of screen doors, and for bracing the frames of such doors.

Conventional screen doors in the most prevalent sizes, vary somewhat in both height and width. Protective and decorative metal push grilles, which fit within the screen door frames, must therefore be made in various sizes. The amount of variation in the size of such doors, does not ordinarily exceed six inches either horizontally or vertically.

Attempts have heretofore been made to design various types of adjustable grilles for screen doors, but ordinarily, the resultant structures lack beauty and/or symmetry, and the adjustable mechanics are evident even to a casual observer.

The principal object of the present invention is to provide a screen door grille which is adjustable both laterally and vertically, and in which the adjustable mechanics are not apparent to a casual observer.

A further object is to provide an adjustable grille in which the adjustable mechanics do not detract from the grace, symmetry or beauty of the grille.

Another object is to provide a grille structure which is both decorative and strengthening to the door frame.

An important object is to provide a grille of this class which is so designed that it may be packaged and shipped in disassembled or knocked-down condition, yet may be reassembled and installed with only a screw-driver being used.

An additional object is to provide an adjustable structure for screen grilles, in which a plurality of scroll bearing slats or arms are used, and in which the number of the slats used may be varied to suit the taste of the individual.

A further object is to provide an adjustable grille structure wherein the decorative slats are made of slightly resilient metal so that their scrolled end portions may be sprung laterally to accommodate frame openings of various widths, thus eliminating all laterally disposed longitudinally adjustable rods or beams, all pivotally mounted laterally swinging arms, and all interchangeable or auxiliary and attachable scroll pieces, which are usually present in conventional adjustable screen door grilles.

Briefly stated, the invention includes a means for rigidly clamping together the straight end portions of a plurality of slightly resilient metal slats or rods, the free ends of which bear decorative scrolls, and holding such straight end portions rigidly mounted in the opening of a screen

2

door frame. The slats are longitudinally adjustable in the clamping means, so that they may be extended various distances therefrom to accommodate frame openings of various heights, and the extended scrolled end portions of the slats may be swung laterally sufficient distances to accommodate frame openings of various widths.

Other objects will be apparent from the following description when taken in conjunction with the accompanying two sheets of drawings, wherein:

Figure 1 is an elevational view of a conventional screen door in which the grille structure of the present invention has been installed, the dotted lines showing possible variation in frame width and height, and the possible scroll-slat adjustment to accommodate such frame variation.

Figure 2 is an enlarged elevational view of a slat clamping mechanism made in accordance with the inventive precept, the dotted lines illustrating the manner in which the mechanism may be made to accommodate different numbers of slats;

Figure 3 is an enlarged fragmentary vertical sectional view through the main body portion or clamping sleeve of the clamping mechanism;

Figure 4 is a horizontal sectional view through the clamping sleeve and showing three scroll slats impinged therein, the dotted lines illustrating the sleeve as it would appear if an additional slat is added, the section having been taken substantially along the line 4—4 of Fig. 2; and,

Figure 5 is a view similar to Fig. 4, but showing a slightly different type of clamping sleeve.

Like characters of reference designate like parts in those figures of the drawings in which they occur.

In the drawings:

The reference numeral 1 indicates as a whole, a conventional screen door or screen frame having an opening described by two vertical parallel side rails 2 and 3, a horizontal top rail 4 rigidly connecting the upper ends of said side rails, and by a horizontal bottom panel 5, which connects the lower ends of the side rails. The opening within the frame 1 is indicated, as a whole, by the reference numeral 6.

The grille of the present invention includes a bracket, composed of two individual sections A and B. In the embodiment illustrated in the accompanying drawings, the bracket section A is formed by bending a single piece of metal strap to form a substantially triangular loop. The loop has a straight horizontal bottom portion 10, an upwardly and inwardly extending straight side

portion 11, and an arcuate side portion 12 which extends downwardly and inwardly to meet the bottom portion 10 adjacent the inner end thereof. The lower end of the arcuate side portion 12 is bent abruptly to extend along and lie flatly upon the upper surface of the inner end portion of the bottom portion 10. This short horizontal end portion is indicated by the reference numeral 13. The inner end of the bottom portion 10, and the horizontal end portion 13, are provided with complementary through slots 14 for receiving a wood screw 25 whereby the bracket section A may be anchored in the frame opening 6 and upon the upper edge of the panel 5.

Attached within the above described loop of the bracket A, there is provided a strengthening brace 15 which is rigidly attached by rivets 16 to the portions 10, 11 and 12 of the loop. In the present instance, the brace 15 is made ornamental as well as useful, but it could well be made to assume any desired configuration, as long as it braced the loop sides against collapse or bending.

The bracket section B also consists of a substantially triangular loop formed by bending a single piece of metal strap. The strap has a straight vertical side portion 17, adapted to be attached to the inner edge of the side rail 3 by wood screws 18. At its lower end, the side portion 17 is abruptly bent upwardly and inwardly to form a straight side portion 19. At the upper end of the side portion 19, the strap is bent abruptly in an outward direction to form a top portion 20 which extends to meet the inner surface of the upper end of the vertical side portion 17. The outer end of the top portion 20 is bent upwardly to extend along the side portion 17, and one of the wood screws 18 passes through the two ends of the strap, and into the side rail 3 of the door frame. The loop of the bracket section B is reinforced by a suitable brace 21 held therein by rivets 22.

That face of the side 19 which lies nearest the bracket section A, is equipped with a longitudinal three-sided channel member 23 having its opening or mouth facing toward the bracket section A. The central span 24 of the channel member 23 is riveted firmly to the side portion 19 of the bracket section B, and is consequently held immovable in the door frame 1.

To the outer face of the side portion 11 of the bracket section A is riveted a similar, but slightly larger, channel member 26 which is adapted to fit over and close the mouth of the first channel member 23 when the bracket section A is moved toward the bracket section B.

The two channel members 23 and 26 complementally form an elongated tubate socket for receiving and embracing the straight lower end portion 29 of a plurality of elongated decorative elements or strips 27. The elements 27 are preferably made of slightly resilient strap metal, and their other end portions are preferably bent to form scrolls or other decorative configurations 28. The bent end portions of the strap elements 27 are perforated to receive wood screws 30, whereby they may be attached in various positions to the inside edges of the door frame rails 2, 3 and/or 4.

In installing the grille of the present invention in the door frame 1, the bracket section B is first mounted on the inside edge surface of the side rail 3, as shown. Two or more of the wood screws 18 are used for this purpose. The bracket section A is next mounted upon the upper edge of the bottom panel 5 of the door, with the wood

screw 25 engaged in the panel, but not tightened down. A desired number of the straight ends 29 of the decorative strap elements 27 are then thrust downwardly into the socket formed by the two channel members 23 and 26. The strap elements 27 are pulled upwardly a desired distance, to make their scroll ends reach a desired height in the frame 1. The wood screws 30 are then installed to hold the strap elements in place.

Some of the strap elements may be fastened to both the upper rail 4 and one of the side rails 2 or 3, while others may be sprung laterally to reach one of the side rails, as shown in Fig. 1 of the drawings. The strap elements 27 are, of course, of different lengths. It is therefore possible to obtain different decorative results by using different numbers of the strap elements, and by positioning their scrolled ends in different places in the frame 1. Since the straight end portions 29 are slidable in the bracket socket, and since the strap elements are bendable or resilient, many different decorative effects may be obtained. Since the socket forming channels 23 and 26 are adjustable toward and away from each other, different numbers of the strap elements may be used.

After the desired number of the strap elements have thus been mounted in the door frame 1, the bracket section A is pushed along the panel 5 toward the bracket section B, and the channel members 23 and 26 are thereby caused to impinge and clamp the end portions 29 of the strap elements 27 firmly together. The wood screw 25 is then tightened down to hold the bracket section A immovable.

If desired, the bottom extent of the bracket reinforcing element 15 and the horizontal portion 10 of the bracket section A may be slotted to receive another one of the wood screws 25. Such a slot is shown in dotted lines in Fig. 2, and is indicated by the reference numeral 31.

While the bracket is shown in the drawings as being mounted in the lower right hand corner of the door frame 1, it is evident that it could well be positioned in any other inside angle of such frame.

In Fig. 1, the solid lines depict the strap elements 27 as they appear when installed within the screen opening of a door of one size. The dotted lines depict a door frame of larger size, and show the strap elements as they would appear when drawn further out of the socket, and after being sprung laterally to accommodate the greater frame width.

It is within the concept of the present invention, that the bracket may be designed for use in other positions in the frame opening than in a corner angle. It is also conceived that the bracket could well be designed to mount on the front or rear face of the door frame, rather than on the inside edges of the elements which bound the screen opening.

In instances wherein only one specific number of the strap elements 27 are to be used, the strap-end receiving socket could well be made of one tubate piece. In such a case, the bracket need not be made in two sections, as shown in the drawings and as described hereinabove, and a square socket such as that shown in Fig. 5, could be used to slidably mount the straight end portions 29 of the strap elements 27. The tubate socket, which is square in cross-section, and which is shown in Fig. 5, is indicated as a whole by the reference numeral 32. The socket 32 is of

a size to properly envelop five of the strap end portions.

Obviously the invention is susceptible to some change or alteration without defeating its practicability, and I therefore do not wish to be confined to the preferred embodiment shown in the drawings and described herein, further than I am limited by the scope of the appended claims.

I claim:

1. An adjustable grille for screen door frames, including: a plurality of elongated strap-like elements having decorative scrolls on one end adapted to be individually anchored in various spaced positions within the opening of a screen door frame, the other ends of said elements being gathered together in flat face to face relationship to each other; a bracket adapted to be rigidly mounted in said frame opening; and a tubate socket carried by the bracket for embracing and anchoring the gathered ends of said elements in various longitudinal positions, said socket including two elongated channel members, one nested within the other to complementally form a tubate socket opening into which said gathered ends of the scroll elements extend, said members being relatively movable laterally to impinge said gathered ends; and means for anchoring the channel members in various relative positions of lateral adjustment.

2. An adjustable grille for screen door frames including: a plurality of elongated strap-like elements having decorative scrolls on one end, said scroll ends being adapted to be individually anchored in various spaced positions within the opening of a screen door frame, the other ends of said elements being gathered together adjacent one corner of said door opening in flat face to face relationship to each other; a bracket adapted to be anchored to said door frame; and a tubate socket carried by the bracket for embracing and anchoring the gathered ends of said elements in various longitudinal positions, said socket including two elongated channel members, one nested within the other to complementally form a tubate socket opening into which said gathered ends of the scroll elements extend, said members being relatively movable laterally to impinge said gathered ends; and means for anchoring the channel members in various relative positions of lateral adjustment.

3. An adjustable grille for screen door frames, including: a plurality of elongated elements having relatively similar end portions bent into deco-

rative configurations, said portions adapted to be individually anchored in various positions within the opening of a screen door frame, the other end portions of said elements being straight and being gathered together in adjacent co-extensive relationship to each other; a bracket adapted to be anchored to said door frame; and a tubate socket carried by the bracket for embracing and anchoring the gathered ends of said elements, said socket including two elongated channel members, one nested within the other to complementally form a tubate socket opening into which said gathered ends of said elongated elements extend, said members being relatively movable laterally to impinge said gathered ends; and means for anchoring the channel members in various relative positions of lateral adjustment.

4. An adjustable grille for screen door frames, including: a plurality of elongated elements having relatively similar end portions bent into decorative configurations, said portions adapted to be individually anchored in various positions within the opening of a screen door frame, the other end portions of said elements being straight, and being gathered together adjacent one corner of said door opening in co-extensive relationship to each other; a bracket adapted to be anchored to said frame adjacent said corner; and a tubate socket carried by the bracket for embracing and anchoring the gathered ends of said elements, said socket including two elongated channel members, one nested within the other to complementally form a tubate socket opening into which said gathered ends of said elongated elements extend, said members being relatively movable laterally to impinge said gathered ends; and means for anchoring the channel members in various relative positions of lateral adjustment.

LOUIS A. MACKLANBURG.
